CLAIM

The ornamental design for a connector for a fitness apparatus, as shown and described.

DESCRIPTION

FIG. 1 is a bottom front left perspective view of a connector for a fitness apparatus, showing my new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front left perspective view thereof, shown in use;

FIG. 9 is another front left perspective view thereof, shown in use;

FIG. 10 is a third front left perspective view thereof, shown in use;

FIG. 11 is a fourth the front left perspective view thereof, shown in use;

FIG. 12 is a fifth front left perspective view thereof, shown in use;

FIG. 13 is a sixth front left perspective view thereof, shown in use;

FIG. 14 is a seventh front left perspective view thereof, shown in use; and,

FIG. 15 is an eighth front left perspective view thereof, shown in use.

The broken lines in the drawings represent portions of the connector for a fitness apparatus and environmental matter, including fitness attachments and accessories, that form no part of the claimed design.

1 Claim, 15 Drawing Sheets
